(57) CLAIM

The ornamental design for a vibrating handle with skin care attachments, as shown and described.

DESCRIPTION

FIG. 1 is a bottom plan view of a vibrating handle with a skin care attachment showing my new design; and,

FIG. 2 is a top right side perspective view of the vibrating handle, wherein the left side view of the skin care attachment is a mirror image of the right side view.

The broken lines represent portions of the vibrating handle with skin care attachments that form no part of the claim.
